David S. Neal

UNITED STATES PATENT OFFICE.

DAVID S. NEAL, OF LYNN, MASSACHUSETTS.

SPEAKING-TUBE FOR SHIPS.

Specification of Letters Patent No. 23,261, dated March 15, 1859.

To all whom it may concern:

Be it known that I, DAVID S. NEAL, of Lynn, in the county of Essex, and State of Massachusetts, have invented a new and very useful instrument called by me a speaking tube, to be kept on board of vessels for the purpose of being used by a shipwrecked crew or passengers for holding communication with people upon the land when within a few hundred feet of the shore; and I do hereby declare that the following is a full and exact description thereof, reference being had to the accompanying drawings and to the letters of reference marked thereon.

Figure 1 D, D, a gutta percha or rubber tube A, A, mouth piece at each end, to be used when unscrewed near keg B, which is used as a float to carry the tube attached on shore, C brass coupling to screw the tube together and lengthening to any required distance, e, e, horns to unscrew and screw to-

gether, the keg B, to have printed upon it, "Please unscrew the keg from the mouth piece and converse with us." Fig. 2, B keg unscrewed from the mouth piece A, e, e, 25 horns. Fig. 3, a mouth piece detached from tube D, D, and unscrewed from pipe in keg B. Fig. 4 c, c, coupling to tube D, D, unscrewed c, c, horns for unscrewing.

Having fully described my invention, I 30 wish it distinctly understood that I do not claim inventing a tube, or, an iron copper or brass bound keg; but

What I claim and desire to secure by Letters Patent, is—

The arrangement of the speaking tube, 35 with a cask or equivalent float, substantially as and for the purpose specified.

DAVID S. NEAL.
